METHOD OF CONSTRUCTING WELDED
METAL WATER-GOING VESSELS

Ludwig S. Baier, Milwaukee, Oreg.

Application November 27, 1939, Serial No. 306,368

10 Claims. (Cl. 114—79)

My invention relates to improvements in the art of ship building and it more particular relates to welded steel construction using the so-called longitudinal system of framing, examples of which may be found in the Isherwood patents, Nos. 1,029,546 and 1,147,732.

More specifically the present invention relates to improvements in methods of framing and the welding of the shapes and plates and welding the plate butts and seams of such vessels.

Further, it is an object to provide a method of construction and design of such vessels by which certain objectionable features heretofore found to occur in welded ship constructions are turned to advantage in my method by which a valuable asset to the ship builder is obtained.

Again, it is an object to provide a method of construction whereby one may predetermine the buckling the plates will take when they are finished welded and whereby one is enabled to prevent buckling ad lib. and the consequent creation of an uneven surface; and, further, a method of welding the plating to the framing (the framing includes the longitudinals, bulkheads—fore and aft and transverse—and the transverse web frames) so as not only to control the buckling but also to minimize the stresses in the plates due to the welding operation.

Further, it is an object to provide a combined liquid cargo and general freight cargo barge that is so designed and constructed that it may be used safely to carry a cargo of oil and/or gasoline, or a cargo of general freight without the one cargo interfering with the other, the filling and emptying ducts for the liquid tanks and the motors and pumps for the same being located outside the general cargo space and having no connection therewith, so that fumes or leakage (if any) from the liquid cargo tanks cannot enter the general freight house chamber or chambers.

Other objects will in part be obvious and in part be pointed out hereinafter.

To the attainment of the aforesaid objects and ends the invention still further resides in those novel features of construction, combination and arrangement of parts, all of which will be first fully described in the following detailed description and will then be particularly pointed out in the appended claims, reference being had to the accompanying drawings, in which:

Figure 1 is a top plan view of a combined liquid and general cargo barge according to my invention, the aft portion having the top plating of the freight house removed to show the framing.

Figure 2 is a side elevation of the same, the side and top plating of the aft portion being removed.

Figures 3^A—3^B, when joined on the line A—B, constitute a top plan view of the hull, the freight house being removed and approximately one half the deck plating being omitted.

Figures 4^A—4^B, when joined on the lines C—D, constitute a midship cross section on the line 10 4—4 of Figure 3^A.

Figure 5 is a detailed longitudinal vertical section on the line 5—5 of Figure 3^A.

Figure 6 is a similar view on the line 6—6 of Figure 3^A.

Figure 7 is a similar view on the line 7—7 of Figure 3^A.

Figure 8 is a diagrammatic plan view of a portion of a vessel showing one method of construction.

Figure 9 is a detailed cross section showing how the web frames, bulkheads, longitudinals and plating are assembled.

Figure 10 is an enlarged detailed view of a 20 portion of the parts shown in Figure 9 showing the method of securing the web frames, and the bulkheads to the longitudinals and the plating to these three elements.

Figures 11 to 20, inclusive, are diagrammatic 25 detailed views hereinafter specifically referred to.

Figure 21 is a detail section showing a portion 30 of the construction involved in my invention.

In the drawings, in which like numerals of reference refer to like parts in all the figures, 1 represents the superstructure or freight house, 35 which is framed by longitudinals 2, uprights 3 of angle iron, flat side bars 4 and roofing 5, all of steel suitably welded together and to the deck beams of the hull to form a rigid structure.

Hatches 6 are provided at suitable intervals.

40 Aft and fore are transverse tight partitions (bulkheads) 7, 8 and 11, 12 which divide the fore and aft ends of the superstructure into two transverse rooms 9, 10 and 13, 14, sealed from one another and from the cargo space amidship. The 45 rooms 9 and 13 are designed to contain the pumps for the loading and the unloading of the liquid cargo of the hull tanks (later again referred to), while the rooms 10 and 14 are designed to contain the motors (preferably Diesel engines) to run the pumps, the connections between motors and pumps passing through gas tight stuffing boxes in the bulkheads 8 and 12.

Entrance is had to the rooms 10 and 14 through water-tight doors 15 and suitably located manholes with gas-tight covers 15^x may be provided

for entrance to the pump rooms in case repairs to pumps become necessary.

Ladders 16 fore and aft give access to the catwalk 17 on the roof of the freight house. The side wall plating 18 of the freight house and the roof plating 19 are of welded construction, and are welded to the framing in any suitable way, or the plating may be secured to the framing in any other desired fashion.

The ventilators for the motor and pump rooms are indicated at 20 (Figures 1 and 2), while 22 indicates the pressure relief valves, 23 the filling and discharge pipes, 24 the port holes, and 21 the coaming.

The hull 25 constitutes the principal part of my invention and will now be described, reference being had particularly to Figures 3 et seq.

The hull includes a set of transverse frames composed of side uprights 26, bottom portions 27 and top or deck-beam portions 28 (see Figure 4A) securely welded together, as at w. These frames are slotted to receive the continuous longitudinals 29 which extend from the foremost transverse bulkhead 35 to the rearmost transverse bulkhead 35 (Figures 3A-B and 6). These longitudinals are securely welded to the cross frames (on one side only if desired) and to the bulkheads on both sides to obtain a fluid-tight joint.

In the design illustrated, three transverse bulkheads 35 and three longitudinal bulkheads 30 are provided, dividing the hull into eight tanks.

The bulkheads 35 and 30 are securely welded to the longitudinals 29, and the deck and shell plates 34, 32, 33 of the vessel, and to each other where they cross, so that each tank will be separate and distinct from the others, the bulkheads also serving to stiffen or brace the hull. To that end I prefer to employ corrugated bulkheads as shown in Figures 3A-B and 4A-B. The use of corrugated bulkheads not only eliminates the cost of attaching additional stiffeners (as the corrugations form a stiffened section), but the top and bottom edges of the bulkheads form butt straps for the deck or shell plate seams (see dotted-line longitudinal bulkhead in Figures 3A-3B).

The cross frames 26, 27, 28 are further braced by diagonals 31 (preferably of angle iron) securely welded as indicated.

At the fore and aft ends the vessel is provided with raised deck portions (see Figures 5 to 7 inclusive).

The centerline longitudinal section at the rakes is provided with a series of longitudinal stiffening partition plates 36 and transverse partition plates 38 and cross frames 39, the plates 36 having holes 37 to lighten their weight and to permit draining.

At the sides of the mid-plane, longitudinal skeleton stiffeners 52, 53 are used, as are also short deck beams 29a, corner braces 54 and diagonal braces 60, all securely welded into an integral structure. By reference to Figures 4A-B, 5, 6 and 7 it will be seen that the raised deck plating 34a runs thwart ship, while the main deck plating 34 runs fore and aft.

The raised deck, fore and aft, provides a set of expansion chambers for the tanks, which chambers are braced by plates 51 (see Figure 6) securely welded in place. The method of welding the plating to the framing will be explained later.

Split pipe fenders 55 are welded on at suitable places (see Figures 2, 4A-B, 5, 6 and 7).

In barge construction, as shown, I prefer to use flat bar for longitudinals as these can be welded to the shell and deck plating in the shop at a great saving in time and money, as down-hand welding can be used. This, of course, would apply to the longitudinals in the straight portion of the barge, namely, between the two peak bulkheads. The ends would be shaped and the plating applied to the bent or cut-to-shape framing. By using flat bar in this manner it will be possible to use the following procedure in assembling the barge: First, the bottom plating, if to be corrugated, is first rolled to a slight set; second, the longitudinals will then be welded to the plating (bottom, side and shell) before leaving the shop; third, a supporting staging with corrugations corresponding to those of the pre-rolled bottom plates is set up and properly faired; fourth, the bottom plating is laid over this staging; fifth, next the web frames, longitudinals and transverse bulkheads are placed and the notches in the transverse web frames and the transverse bulkheads are aligned with the flat bar longitudinals of the bottom plating; sixth, the side plating with the longitudinals attached is placed in position with the notches engaging the longitudinals and the same applies to the deck plating throughout the square portion of the hull; seventh, the raked or spoon ends, as the case may be, are framed from bent or cut members and secured to the peak bulkheads, and are shored to position and then plated over; eighth, the bilge plate, if any, will be applied last, and as the bilge plate may be rounded instead of angular (Figures 4A and 4B) it should be rolled on a slightly shorter radius than that of the bulkhead so as to allow for contraction after the edges have been welded (see Fig. 18). There is no stem or keel on a barge of this type. The centerline longitudinal bulkhead takes the place of a keel and in the erection of the barge would not be placed first, but as mentioned above.

The longitudinals 29 may be of flat bar section, as shown in Figures 4A-B, or they may be of angle section as shown in Figures 8 to 10 inclusive.

When angle bars 60 are used I prefer the construction shown in Figures 8 to 10 inclusive, by reference to which it will be seen that the bulkhead plates 58 have angle slots 59 through which the longitudinals 60 are passed, after which the angle-bar longitudinals are securely welded all around, as at w, to close entirely the space between bars 60 and the bulkhead 58, as well as to unite them into an integral structure. The plating 61-62 is welded to the bulkhead plates 58 and the outer edge of the longitudinals for the full length of their contacting faces so that no fluid may pass by the bulkhead from one compartment or tank to another. When the angle-iron longitudinals are used, the web frames 57, 57a are not slotted but have edge contact only with the inner flanges or webs of the longitudinals (see Figures 9 and 10).

This construction has a number of advantages over ordinary practice, especially in ship construction for hulls up to 250 feet long (see Figure 8). For instance, after the lines of a boat are laid down in the loft and faired, the following sections of the hull are molded in template form: keel, stem, transom, fantail, transverse web frames, bulkheads, deck plating and ma-

chinery foundations. The longitudinal frames are merely sprung into position in assembling and require no laying out or templates for the same.

In a transversely framed hull it is a costly and slow job to bend each individual frame to a special set and requires much skill to obtain fair lines. With transverse framing it is also necessary to keep the frames properly spaced and in alignment by the use of ribbands and shores until such time as the plating can be applied and secured. Thus, I can safely say, the fabrication and erection as compared to the method I have devised is at least twice as costly.

To go into more detail, I shall take up the construction step by step in order that one may better understand the advantages, etc. of my method.

As soon as the loft work is far enough along to start duplicating steel, the first items to be placed are the keel and stem iron when building a boat. The web frames and transverse bulkheads are then set up and shored in position and in proper relation to each other. Then the longitudinals (angles) are sprung into place cold. As mentioned before, there is no bending or fabrication necessary. Angle shapes are used for all longitudinal frames. In a boat fifty feet and under it is practicable to fit these longitudinals in one long bar. This insures a fair curve the length of the hull and can be compared with a ribband or batton used to fair up the wooden frames in a wood boat where steamed frames are used. A number of longitudinals are threaded through the slots provided in the bulkheads, either side of the hull. Then in pairs, one port and one starboard, they are sprung into place at the transom and secured by welding; the forward ends are sprung into place then, and secured by welding at the stem. By springing the longitudinals in pairs any tendency to distort the hull is eliminated as there is an equal pressure applied at either side of the hull and one offsets the other.

It will be noted in the accompanying drawings, Figures 8 to 10, that in way of the web frames no slots are provided to retain the longitudinals. Instead, the frames 57-57^a (web frames) are marked while being laid out and center-punched at the point where the longitudinal passes. A light tack weld at this point will hold the longitudinal in position until further welding is required.

The transverse web frames may be of single plates for small craft or of a number of plates welded together. This is merely a matter of design and judgment on the part of the builder so long as strength requirements of the classification societies are satisfied. As will be noted, the transverse frames do not carry out to the molded line, i. e., inside of the shell plating. Only the bulkheads are full width and these are slotted in way of the longitudinals. The reason for not carrying the web frames out to the plating is that it entails more labor to slot or notch the webs and the method of springing the longitudinals would be considerably slower. Further, the added welding would not add strength to the hull with this system of framing, but would tend to cause the plating to show a buckle. Such a buckle may be encountered where the transverse bulkheads are welded and may require additional labor to fair the plating out at this point after the welding is completed, or means used to absorb the heat by using dry ice (or other cooling

means) while the welding is being done, especially where light gauge metals are used. Thus considerable labor is saved in not welding the web frames directly to the shell and deck plating.

After all the longitudinals are in place, both on the shell and the deck, the boat is ready for plating. Before going into the methods used here, I wish to point out that when a vessel of any kind is welded there is a certain amount of contraction after the weld has been made, which if not relieved causes considerable stress. In some instances sufficient stress is locked up to cause the weld to fail. It is easy to see then, that in a shape such as a boat, that after all the hull and deck plating are welded in place, if there is nothing done to permit this plating to "shrink," a strain would be placed on both the plating and on the supporting frames. The usual result in boats framed in the conventional manner (i. e., transversely) is to have the frames or ribs protrude like those of a skinny horse. The plating being drawn taut by the welding process is in tension, the frames in compression. This is not only unsightly, but is undesirable from a structural and engineering standpoint. In smaller items being welded stress-relieving is accomplished by means of heat treatment and annealing. This method, of course, is not practicable or possible in the building of a boat; therefore it is necessary to prevent, as much as possible, any stress occurring while the plating is being welded in place. As has previously been mentioned, all longitudinals are merely tacked sufficiently to hold them in place so that the plating can be secured thereto. In addition, the slots in the bulkheads are slightly larger than the cross section of the angle passing through and at these points no welding is used to hold the longitudinal, the slot being sufficient to answer the purpose. (The final welding of this connection will be taken up later.) The bulkhead plates are merely bolted together sufficiently to permit movement in the bolt holes, so that when the shell and deck plating is welded into place there is sufficient play in the bolt holes to permit the hull to "shrink." Web frames likewise are left bolted until after all outside plating is finally welded.

All plating, whether on the deck or shell, is started amidship and worked toward the ends and outboard, being welded in that order. The only exception is the bilge plates which are welded on last and allowance for shrinkage is made by rolling them slightly smaller in radius than the framing they cover. When finally welded they will be found to fit closely. By having a small space between the plate and the frames at the center of the rolled plates, and by welding both the top and bottom edges of such a plate, the weld, when cool, will take up the slack, and the plate will thus position itself.

When all welding on the exterior of the shell and deck has been completed, the interior welding is commenced. First the bulkheads are welded to the shell; then all web frames are welded to the longitudinals and slots inway of the bulkheads where the longitudinals pass through are welded. Bulkheads and web frames, when made up in sections, have the sections lapped and secured together with bolts. The bolts, being smaller than the soles provided for them, permit the plating to contract to a degree sufficient to help relieve the stress caused by welding. In short, the hull when welded in this manner will be slightly undersize, but not enough to be noticed

and the stress being relieved thereby will insure a stronger hull. It is also desirable to do the same amount of welding at the same time port and starboard. This means, of course, employing an equal number of welders to work both sides of the boat, and that they should work opposite one another at all times.

Where stop-waters are used in way of water and oil tight bulkheads, longitudinals will be nicked or notched out sufficiently to permit the weld to penetrate to the depth of the bar and fuse with the shell and/or deck plating. All stop-water notches will be cut only after the hull and deck plating is welded. To notch for stop-waters before the plating is finished being welded would tend to put a kink in the longitudinal at the point where the notch occur red and would cause an unfair curve on the shell as a result. There is no danger of this happening after the shell is once secured and amply welded.

From the foregoing description, taken in connection with the accompanying drawings, it will be seen that by following my invention the following advantages are present:

1. A system of framing so spaced and connected as to eliminate distortion of the plating welded thereto.
2. A system of framing eliminating the necessity of furnace and slab work and/or other mechanical means of bending and setting frames.
3. A system of framing which can be easily faired and which will prevent stresses in the hull due to the welding of plates to frames, longitudinals, etc.
4. A system of framing that will be more economical than any method now used, both from the standpoints of fabrication and erection.
5. A system of framing employing light-weight, easily shaped angle iron shapes, spaced sufficiently close together to give effective stiffening to the plates welded thereto and at the same time not causing any distortion of the plating when the same is being welded.
6. A system of framing that uses transverse bulkheads and web frames spaced at intervals, depending on the size of the boat, so that the longitudinal framing may be sprung in such a manner as to bring a fair curve to the shell and deck portion of the boat.
7. A system of framing that will permit longitudinals to be applied to the hull without previous fabrication, except cutting to the proper length.
8. A system of framing that will permit the use of standard structural and shipbuilding shapes of angle.
9. A system of framing combining the use of web frames, bulkheads and longitudinal frames of such size and strength as necessary to conform to the requirements of the classification societies.
10. A system of framing so arranged as to allow for the natural contraction of the metals after being welded together to form a hull consisting of web frames, bulkheads, longitudinal framing and exterior plating.
11. A system of framing that will permit the use of smaller welds without lessening the strength of connections, as more welds will be employed over a greater area, thus holding welding heat to a minimum and eliminating buckling ordinarily caused by too great a heat being applied at one point.
12. A system of framing so arranged as to afford the greatest stiffening at the lowest cost per pound of finished job.

13. A system of framing so arranged as to give a more uniform distribution of stiffened support and at the same time be flexible enough to withstand severe shock.

14. A system of framing so arranged as to take up the shock of collision, rather than crack or rupture.

15. A system of framing easily repaired in the event of serious damage due to collision.

10 16. As to the method of design with relation to the welding operation, in constructing barges or amidship portions of large boats, the method here presented is based on facts well known to those who have used welding for connecting plates and shapes and welding plate butts and seams of boats. We know that the base metal expands and then contracts when welded. The result is buckling and warping; sometimes fracture, due to built-up stresses where there is little chance for the metal to "go," occurs. These are the most objectionable faults in welded construction. By employing the invention here involved I am able to utilize these faults and make them instead a valuable asset to the shipbuilder.

20 Counting some of these features directly in favor of my ideas, I am listing the following:

1. A stronger hull per pound of dead-weight for given dimension.

2. Lower first cost.

3. Lower operating cost.

4. Elimination of 90% overhead welding.

30 5. Complete welding of over 75% of the job in the shop.

6. The use of high strength and high speed rods on automatic welding machines as the result of features 4 and 5.

35 7. Ease of erection and assembly on the ways.

8. Use of present shop equipment, making it unnecessary to install special equipment (except welding machines and jigs).

40 The basic principle involved in this phase of the invention is one of shaping the plates so that a predetermined direction will be followed when the work is welded and so the work will not buckle and warp "hit or miss." Along with the shaping of the plates, longitudinal framing is employed. While the latter has been used for many years in ship construction and is in itself nothing new, it is none the less necessary to use this type of framing.

45 This system lends itself more particularly to the bottom and side plating on barges and bulk carriers such as are used on the Great Lakes and in coastwise trade, including tank ships. It is claimed that a lighter-weight plate, together with lighter-weight framing, can be used and give the same section modulus to that of a hull plated with flat plates of a greater thickness and using heavier framing. This is in addition to the feature of stress relieving. Also in welding a seam of a plate having a slight set, the amount of welding required to make a longitudinal seam connection can be reduced as the action of the plate after being welded tends to flatten out due to the contraction of the base metal after the weld has cooled, thus relieving the stress on the weld and plating adjacent to the line of the weld. In all cases the butts would be welded first, before welding the seams transversely.

50 By having the buckle predetermined in a fore-and-aft direction, as will be the case here, the hull will offer less frictional resistance to the water when under way than if the framing is run transversely and the plating applied flat or without set.

55 70 To illustrate the point, Figures 11 and 12, show-

ing the action taken by plates after being welded, will clearly prove my case. In Figure 11 is shown a butt weld made on two unprotected flat plates, the dotted lines indicating the distortion of the plate after welding. The solid lines indicate the position of the plates before being welded, being perfectly flat. In Figure 12 it will be noted that before welding the two plates at the butt, they have been rolled to a slight "set." After the butt is welded the plates are practically in the same shape as before welding, as the figure indicates. These figures in perspective are exaggerated purposely.

In Figure 12 one of the principal features is embodied. Modifications of the basic idea can be used in a number of ways.

To illustrate further the action of welding to the base metals, Figure 13 shows a plate and shape welded in a T section. Figure 14 shows a plate slightly rolled and welded to an upright member, also forming a T section. The solid lines indicate, in Figure 13, the plates before welding, the dotted lines after welding. In Figure 14 it will be noted the draw of the plate is in line with the original shape, but slightly less.

In Figures 15, 16 and 17 I have shown by exaggerated cross-sectional diagrams the results produced by my method. In Figure 15 the plates are shown with the set given them in rolling. Figure 16 shows the longitudinals welded to the plates and part of the "set" removed as the draw caused by welding tends to flatten the plates. Figure 17 shows the shape of the plates after being welded at the seams. In practice the amount of original "set" is about one inch in eight feet. After all welding is completed, the set is about thirteen-sixteenths of an inch in eight feet, about one-eighth of an inch being removed when longitudinals are welded to loose plates and about one-sixteenth of an inch when seams are welded.

Allowance will have to be made for this draw in rolling the plate. If we assume that Figure 17 is representative of a section of the bottom shell, it will be noted that the heavy bead will be put on from the inside of the ship, which means a down-hand weld and of course the use of coated electrodes with their higher tensile strength. The overhead weld serves two principal functions. One is to add to the strength of the weld by closing the open edge of the seam, thereby preventing fracture that might be caused by lack of penetration of the heavy bead, and the second is that the smaller bead acts to anneal the larger weld, thereby eliminating to a degree stresses built up along the line of the weld. It will also be noted that the plating in this position especially adapts itself to a predetermined shape, namely, that the action of the draw in the metal is in the direction of the pre-rolled plate.

With longitudinals welded to plates in the manner shown it is impossible for a cross member, such as a bulkhead, to cause any buckling to take place when the latter is welded to the plating.

In short, by having a "set" and/or roll in the plating transversely, it is possible to have a hull that will offer the minimum of frictional resistance to the water, as the effect is that of a longitudinally corrugated shell.

One of the principal reasons for corrugating the plating in the manner shown—so far as a barge is concerned—is to afford a "grip" to the water and prevent side-slip in fast water, as a smooth bottom would be difficult to navigate in

fast water. So here the corrugations add another good reason for their being, aside from the added strength and smooth longitudinal surface offered. In the case of the large sea-going ship, the amidship portion of the hull, not having shape, may and could be framed much like the barge referred to, with the shaped bow and stern built up of curved members and then plated over. The uncurved portions of the hull of a boat up to 400 feet long could be constructed to advantage similar to the construction followed in erecting a barge. In this case the longitudinals themselves would be notched in way of the bulkheads and the top leg or flange of the angle would be slotted, as at 63, to clear, instead of notching the bulkhead and threading the angle through as in the smaller hull of fine lines (see Figure 19). The bulkhead or web frame—if the latter extends to the hull—would be notched as at 64 for the standing flange of the longitudinal (see Figure 20). The corrugating of the bottom plates would be possible on a boat of this size, together with the side plating up to a point where the bow and stern curves start.

Of course it will be obvious to those skilled in the art that changes in the details of construction can be made without departing from the present invention.

What I claim is:

1. The method of metallic ship construction which comprises the following assembly steps in the order mentioned: placing the keel and stem irons in position, setting up a fore and an aft transverse bulkhead and the transverse web frames with the respective parts of the web frames connected and shoring the same in position in proper relation to each other, threading longitudinals of angle shapes in pairs, one at each side of the hull, through corresponding angle slots in the bulkheads with a flat side of the angle shapes against the frames, and springing the longitudinals into place cold, securing the sprung longitudinals to the transom and to the stem by welding, applying the shell plating to the frame, and welding the same to the longitudinals and to the transverse bulkheads.

2. The method of metallic ship construction which comprises the following assembly steps in the order mentioned: placing the keel and stem irons in position, setting up a fore and an aft transverse bulkhead and the transverse web frames with the respective parts of the web frames connected and shoring the same in position in proper relation to each other, threading longitudinals of angle shapes in pairs, one at each side of the hull, through corresponding angle slots in the bulkheads, springing the longitudinals in place cold, securing the sprung longitudinals to the transom and to the stem by welding, applying pre-formed transversely curved shell plating to the frame, and welding the plating sections together and to the longitudinals and to the bulkheads to produce an integral structure.

3. The method of ship construction which comprises the following assembly steps in the order mentioned: placing the keel and stem irons in position, setting up the transverse bulkheads and the transverse web frames with the respective parts of the web frames connected and shoring the same in position in proper relation to each other, threading longitudinals of angle shapes in pairs, one at each side of the hull, through slots in the bulkheads, springing the longitudinals into place cold, securing the sprung longitudinals to the transom and to the stem by welding, applying

the shell plating to the frame and welding the same to the longitudinals and to the transverse bulkheads, and after all outside plating has been finally welded, welding together the parts of the respective web frames.

4. The method of ship construction which comprises the following assembly steps in the order mentioned: placing the keel and stem irons in position, setting up the transverse bulkheads and the transverse web frames with the respective parts of the web frames connected and shoring the same in position in proper relation to each other, threading longitudinals of angle shapes in pairs, one at each side of the hull, through slots in the bulkheads, springing the longitudinals into place cold, securing the sprung longitudinals to the transom and to the stem by welding, applying transversely curved shell plating to the frame, welding the plating sections together and to the longitudinals and to the bulkheads to produce an integral structure, and after all outside plating has been finally welded, welding together the parts of the respective web frames.

5. The method of ship construction which comprises the following assembly steps in the order mentioned: placing the keel and stem irons in position, setting up the transverse bulkheads and the transverse web frames with the respective parts of the web frames connected and shoring the same in position in proper relation to each other, threading longitudinals of angle shapes in pairs, one at each side of the hull, through slots in the bulkheads, springing the longitudinals into place cold, securing the sprung longitudinals to the transom and to the stem by welding, applying the shell plating to the frame and welding the same to the longitudinals and to the transverse bulkheads, welding the marginal edges of the web frames to the longitudinals, and finally welding together the parts of the respective web frames.

6. The method of ship construction which comprises the following assembly steps in the order mentioned: placing the keel and stem irons in position, setting up the transverse bulkheads and the transverse web frames with the respective parts of the web frames connected and shoring the same in position in proper relation to each other, threading longitudinals of angle shapes in pairs, one at each side of the hull, through slots in the bulkheads, springing the longitudinals into place cold, securing the sprung longitudinals to the transom and to the stem by welding, applying transversely curved shell plating to the frame, welding the plating sections together and to the longitudinals and to the bulkheads to produce an integral structure, welding the marginal edges of the web frames to the longitudinals, and finally welding together the parts of the respective web frames.

7. The method of ship construction which comprises setting up the keel, stem, and stern or transom, locating fore and aft transverse bulkheads in position on the keel, the bulkheads having angle-bar-receiving angle slots, locating mechanically extensible and contractible transverse web frames on the keel between the fore and aft bulkheads, threading angle-longitudinals through the bulkhead slots, simultaneously springing a longitudinal at one side of the ship and the corresponding one at the other side together at one end of the ship and welding the longitudinals at said end, then springing the other ends of the same longitudinals into place at the other end of the ship and welding the same in place, placing the shell plating and welding it together and to said longitudinals and to the adjacent edges of the bulkheads, welding the transverse web frames and shell plating together, and finally after the web frame sections have received their "set" welding those sections together, by virtue of which a unitary structure is produced.

8. The method of claim 7 wherein the shell plates are given a transverse curve before they are applied to the frame and have their ends joined by welding the joints between adjacent ends, and welding together the adjacent sides of adjacent shell plates.

9. The method of metallic ship construction which comprises the following assembly steps in the order mentioned: placing the keel and stem irons in position, setting up a fore and an aft transverse bulkhead and the transverse web frames with the respective parts of the web frames connected and shoring the same in position in proper relation to each other, threading longitudinals of angle shapes in pairs, one at each side of the hull, through corresponding angle slots in the bulkheads, and springing the longitudinals into place cold, securing the sprung longitudinals to the transom and to the stem by welding, applying the shell plating to the frame, welding the same to the longitudinals and to the transverse bulkheads, the shell plates being given a transverse curve before the plates are applied to the frame, welding the joints between the adjacent ends of the plates, and welding together the adjacent sides of adjacent shell plates.

10. The method of metallic ship construction, which comprises the building of the frame of the vessel, applying the shell plating to the frame and welding the same to the longitudinals and to the transverse bulkheads of the vessel, the shell plates being given a transverse curve before the plates are applied to the frame, welding the joints between adjacent ends of the plates, and welding together the adjacent sides of adjacent shell plates.

LUDWIG S. BAIER.
